UNITED STATES PATENT OFFICE.

FRANKLIN S. MCKENNEY, OF DETROIT, MICHIGAN, ASSIGNOR OF ONE-HALF
TO J. M. LONGYEAR, OF MARQUETTE, MICHIGAN.

DESIGN FOR A SETTING-DIE.

SPECIFICATION forming part of Design No. 26,076, dated September 22, 1896.

Application filed December 9, 1895. Serial No. 571,596. Term of patent 14 years.

To all whom it may concern:

Be it known that I, FRANKLIN S. MCKENNEY, a citizen of the United States, residing at Detroit, county of Wayne, State of Michigan, have invented and produced a new and original Design for a Setting-Die; and I declare the following to be a full, clear, and exact description of the same, reference being had to the accompanying drawings, which form a part of this specification.

In the drawings, Figure 1 is a view in perspective, disclosing my design. Fig. 2 is a view partly in cross-section and partly in elevation. Fig. 3 is a plan view looking toward the face of the die. Fig. 4 is a partial sectional view on the line 4-4, Fig. 3.

The leading feature of my design comprises the setting-die face A'. The die-face is formed

with a circular cavity, the cavity extending inward from the edge of the die-face and formed at the base thereof with a slightly-elevated thin guiding rib or ridge a, separating the base of the cavity into two portions a' a''. The dividing rib or ridge a terminates before reaching the peripheral edge of the die-face.

What I claim is—

The design for a setting-die herein shown and described.

In testimony whereof I sign this specification in the presence of two witnesses.

FRANKLIN S. MCKENNEY.

Witnesses:

N. S. WRIGHT,
M. A. MARTIN.
